US00D810062S

(12) **United States Design Patent** (10) **Patent No.:** **US D810,062 S**
(45) **Date of Patent:** **** Feb. 13, 2018**

(54) **MOBILE PHONE**

(71) Applicant: **LG Electronics Inc.**, Seoul (KR)

(72) Inventors: **Hophil Lee**, Seoul (KR); **Yooshin Ahn**, Seoul (KR); **Seungbeom Park**, Seoul (KR); **Hyunchul Kim**, Seoul (KR)

(73) Assignee: **LG Electronics Inc.**, Seoul (KR)

(**) Term: **15 Years**

(21) Appl. No.: **29/531,648**

(22) Filed: **Jun. 29, 2015**

(30) **Foreign Application Priority Data**

Dec. 31, 2014 (KR) 30-2014-0064566

(51) **LOC (11) Cl.** **14-03**

(52) **U.S. Cl.**

USPC **D14/248**

(58) **Field of Classification Search**

USPC .... D14/138 AA, 138 AB, 138 AD, 138 AC,

(57) **CLAIM**

The ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof; and,

FIG. 6 is a bottom plan view thereof.

The broken lines depict portions of the mobile phone that form no part of the claimed design. The dash-dot broken lines define the bounds of the claimed design and form no part thereof.

1 Claim, 5 Drawing Sheets
